THE MORRIS PETERS CO., PHOTO-LITHO., WASHINGTON, D. C.

UNITED STATES PATENT OFFICE.

HARRY G. TURNER, OF PHILADELPHIA, PENNSYLVANIA.

APPARATUS FOR BORDERING LETTER-PAPER.

SPECIFICATION forming part of Letters Patent No. 675,803, dated June 4, 1901.

Application filed July 24, 1900. Serial No. 24,713. (No model.)

To all whom it may concern:

Be it known that I, HARRY G. TURNER, a citizen of the United States, residing in the city and county of Philadelphia, State of Pennsylvania, have invented a new and useful Improvement in Machines for Laying Out Cards, Papers, Envelops, &c., for Bordering, which improvement is fully set forth in the following specification and accompanying drawings.

10 My invention consists of an improved construction of a machine for laying out cards, papers, envelops, or other material for bordering wherein the action of the hand is aided in laying out said material on a suitable platform, so that each sheet or piece may leave uncovered as much of the next below it as is to be covered with the bordering-pigment.

15 To the above end the invention consists of a novel construction of mechanism for raising and lowering or rocking suitable gage-pins or similar devices and at the same time simultaneously imparting at the proper intervals a step-by-step movement to the platform, said gage-pins or gage-arm being depressed toward 20 the platform for the next sheet to be moved up thereto.

It also consists of a novel construction of 25 adjusting device, whereby the width of the border is regulated according to requirements.

30 It also consists of novel means for enabling the platform after the same has traveled to its extreme rear position to be readily restored to its extreme forward position.

It further consists of novel details of 35 construction, all as will be hereinafter fully described, and particularly pointed out in the claims.

40 Figure 1 represents a plan view of a machine for laying out cards, papers, envelops, &c., for bordering embodying my invention. Fig. 2 represents a side elevation, partly in section, of Fig. 1. Fig. 3 represents, on an enlarged scale, a side elevation of one of the adjustable gage-pins and its adjuncts employed. Fig. 4 represents, on an enlarged scale, an end elevation of Fig. 3. Fig. 5 represents, on an enlarged scale, a perspective view of an end of the platform, having a sheet of suitable material thereon, showing also the 45 clamping device carried thereby.

50 Similar numerals of reference indicate corresponding parts in the figures.

Referring to the drawings, 1 designates the bed or framework of the machine, the same being provided with the parallel guides or 55 grooves 2, upon which the platform 3 is adapted to travel, the movement of said platform being effected by means of the flexible connection 4, which is actuated by a treadle or pedal and which passes over the pulley 5 and has 60 a connection to the end 6 of the arm 7, which latter is fast on the rod 9, which carries the arm 10, located at about the center of the machine, to the extremity of which latter arm is attached the upright post 11, whose upper end 65 is connected to the arm 12, which moves in unison with the arm 10, it being understood that said arm 12 is mounted on a rod 13 above the rod 9, both of said rods being suitably journaled in the brackets 14. The proper position of the frame 15, which is formed by the post 11 and the arms 10 and 12, is assured by means of the cord 16, which is connected to the lower end of the arm 7 and passes over the pulley 17, said cord 16 carrying the weight 70 18, although it will of course be understood that, if desired, a spring or other equivalent device may be used in place of said weight.

75 When the cord 4 is actuated in the direction of the arrow *a*, a pull will be imparted to the arm 7, whereupon the frame 15 will be first elevated, carrying with it the angularly-arranged rods 19, attached thereto, said rods supporting the heads 20, which are held in the desired position thereupon by means of the 80 set-screws 21 or similar devices and being situated at an angle of forty-five degrees to the line of movement of the platform.

85 The heads 20 are provided with openings in which the gage-pins 23 are movably mounted, each of said pins having the guide or projection 24, which travels in the upright slot or groove 22. The gage-pins 23 are provided with the lower shoulders 26, having lips 90 25 projecting therefrom, and between the 95 shoulders 26 and the bottom of each head 20 is interposed the spring 27, wherefrom it will be seen that the normal tendency of said spring is to depress the point of the gage-pin toward the platform 3 or the material carried 100 thereby, the projections 24, carried by said pins, serving to limit the downward movement of said pins. A pull on the connection 4 will move the arm 7 to the right until the

latter contacts with the end 30 of the lever 28, which is fulcrumed at 29, said lever having attached thereto one end of the spring 31, the other end of the latter being secured to a suitable fixed point 32.

33 designates a connection leading from the end 34 of the lever 28 to the end of the clamp 35, which is loosely mounted on the rod 36, the ends of which are carried by the supports 37, which are attached to the platform 3. The clamp 35 has an opening 38 therein of greater diameter than the diameter of the rod 36 and is held in the proper position by means of the spring or other tension device 39, the latter having one end attached to the upper portion of said clamp, while the other end is secured to a suitable fixed point or strip 40. 41 designates a second clamp which is also loosely mounted upon the rod 36 and has attached to its lower extremity one end of the spring 42, the other end of the latter being secured to the fixed point or arm 43, the upper extremity of said clamp 41 being held between the strips 40 and 8.

25 44 designates a cord or other connection having one end attached to the lower extremity 45 of the clamp 41, its other end being attached to the lever 46, which is fulcrumed at 47. 48 designates a second cord having one end attached to the lever 46, while its other extremity is secured to the upper end 49 of the clamp 35, wherefrom it will be seen that a pull on the lever 46 in the direction of the arrow *b* will cause the clamps 35 and 41 to stand at a right angle or in an upright position with respect to the rod 36, whereupon the platform 3 can be moved as far in either direction as may be desired.

If desired, of course, the cord 44 and the cord 48 may be made of a single cord and passed through an opening in the lever 46 or over a pulley, it being thus seen that the same can be made either in two pieces or one.

50 designates a stop or abutment which is preferably formed of wire or other suitable material and depends from the member 51, which latter may be attached to the adjustable plate 52, adjacent to which is located the scale 53, the desired position of the plate 52 and the stop 50 being assured by means of the set-screw or other fastening device 54.

In practice it is desirable to place upon the platform 3 a sheet of paper, pasteboard, or other suitable material 55, the same being held in position by means of the clamping devices 56, the latter consisting of a lever 57, fulcrumed at the point 58 and having the eccentric curved or arc-shaped groove or slot 59 therein, the walls of said groove being engaged by a pin 60, which is carried by the clamping member 61, which latter has the lip 62, which engages the sheet of material 55, said clamping member having a slot 63 therein, through which passes the pin 64, which is secured in the platform 3, whereby the member 61 is effectively guided in all its movements.

65 designates sheets of the material spaced.

The operation is as follows: A sheet of paper is first placed in position with its edges in contact with the extremities of the pins 23, which are now in their lowest position. A pull on the connection 4 will cause a movement of the arm 7 and raise the frame 15, rods 19, and the gage-pins 23 and their adjuncts. A further pull on the connection 4 will cause the lower extremity of the arm 7 to contact with the end 30 of the lever 28, whereupon the connection 33 will move in the direction of the arrow *c*, and by reason of the tension of the spring 39 the wall of the opening 38 will bite the rod 36 and an intermittent movement will be imparted to the platform 3, the stop 50 limiting the extent of rearward movement of the lever 28, as will be evident. The weight 18 restores the parts to their normal position, and each time the treadle (not shown) is depressed or a pull exerted upon the connection 4, as explained, it will be seen that the frame 15 will be elevated and the platform 3 simultaneously advanced. When the gage-pins 23 are in their lowest position, each successive sheet is fed up to them and the sheet is held in place by the hand of the operator, while the treadle (not shown) is depressed, thereby causing the gage-pins to be clear of the sheet, at which period the platform is propelled a step or the width of the border desired. The pedal is released, and the gage-pins descend upon the sheet that has last been laid in position, and another sheet is fed to said gage-pins, and so on, until the platform is full, when the sheets are removed to the desired place to have the pigment applied to the edges thereof.

105

The width of the border is regulated by the adjustment of the stop 50, since when it is locked at its extreme left-hand position the outer end of the lever 28 will move a greater distance than when the stop 50 is in its extreme right-hand position, and hence the clamp 35 moves back a greater distance on the rod 36, and when it bites the latter will cause the same to move a greater distance than when the stop is in its right-hand position, and any intermediate adjustment can be made.

110

66 designates a stop situated in the path of the clamp 35, which limits the forward movement thereof and prevents the platform from being jerked too far. The clamp 41 prevents the platform from moving backward after a step forward has been taken. After the platform has been filled it is drawn back to the extreme opposite position, which reversing of said platform is effected as follows: The lever 46 is operated in the direction of the arrow *b*, (seen in Fig. 1,) wherefrom it will be apparent that the clamps 35 and 41 will stand in a substantially upright position or at right angles to the rod 36, whereupon said platform can be readily moved to its extreme right-hand position, (seen in Figs. 1 and 2,) according to requirements.

115

120

125

130

When it is desired to border envelopes, one of the gage-pins is removed, leaving one pin on each branch of the gage-rod 19, the gage-pins being then placed at an equal distance 5 from the crotch or angle of the gage-rod and far enough apart to allow the corners of said envelopes to fit between said gage-pins. The springs on the gage-pins take up any unevenness of the paper and insure a proper connection 10 at all times. The gage-pins are provided with the lips 25, which assist to guide the paper to the pin and keep the same flat to prevent curling of said paper, said lips being placed upon the pins so as to be always an 15 equal distance above the point of contact.

The function of the slot 19^a in the rod 19 (shown in Fig. 3) and of the set-screws 21 is to allow for centering, whereby the pins 23 are always retained in a perpendicular position. 20

It will be apparent that by constructing the frame 15 with the parallel arms 10 and 12 the gage-pins will always when in operative position be perpendicular and descend in a 25 proper manner upon the paper.

It will be apparent that slight changes may be made by those skilled in the art which will come within the scope of my invention, and I do not therefore desire to be limited in every 30 instance to the exact construction I have herein shown and described.

Having thus described my invention, what I claim as new, and desire to secure by Letters Patent, is—

35 1. In a machine for laying out cards, papers, envelopes, &c., for bordering, the combination of a frame, a movable platform thereon, a movable frame mounted above said platform, spring-actuated gage-pins mounted on said frame, a rod attached to said platform, clamps engaging said rod, and means for raising and lowering said gage-pins and actuating one of said clamps.

2. In a machine for laying out cards, papers, envelopes, &c., for bordering, the combination of a frame, a movable platform thereon, angular rods supported above the latter, heads on said rods, gage-pins movably mounted in said heads, slots in said heads, projections from said pins movable in said slots, shoulders on the lower portions of said pins, and springs intermediate said heads and shoulders. 50

3. In a machine for laying out cards, papers, envelopes, &c., for bordering, the combination of a frame, a movable platform thereon, a rod attached to the bottom thereof, a clamp through which said rod passes, a spring for holding the upper end of said clamp in position, a lever suitably fulcrumed, a connection from the lower end of said clamp to said lever, and means for rocking said lever. 55

4. In a machine for laying out cards, papers, envelopes, &c., for bordering, the combination of rods 9 and 13 suitably supported, arms 10 and 12 projecting therefrom, an upright post 11 joining the ends of said arms, 60

angular rods 19 supported from said arms and post, heads mounted on said rods, spring-actuated gage-pins mounted in said heads, 70 grooves in rods 19 for centering said heads, an arm 7 depending from said rod 9, a frame, a movable platform thereon, means for actuating said arm 7, and mechanism common to said latter arm and said platform, whereby 75 an intermittent movement is imparted to the latter.

5. In a machine for laying out cards, papers, envelopes, &c., for bordering, the combination of a frame, a platform thereon, a rod 80 attached to the under side thereof, spring-actuated clamps mounted on said rod, means for intermittently actuating one of said clamps, spring-pressed gage-pins supported above said platform, and means for raising and lowering said gage-pins. 85

6. In a machine for laying out cards, papers and the like, for bordering, the combination of a frame, a platform thereon, one or more gage-pins supported above said platform, a lever 7 operating to raise and lower the gage-pins, a second lever 28 engaged and operated by the lever 7, and giving a step-by-step movement to the platform, stops for limiting the movement of said lever 28, one of 95 said stops being made adjustable and connected with a movable plate, and a scale adjacent to said plate.

7. In a machine for laying out cards, papers, envelopes, &c., for bordering, the combination of a frame, a platform thereon, a rod attached to the lower portion thereof, spring-actuated clamps through which said rod passes, means for intermittently actuating one of said clamps, and devices for enabling 100 the movement of said platform to be reversed, consisting of a lever 46 suitably fulcrumed, and a connection leading from the top and bottom of said clamps respectively to said lever, whereby said clamps can be actuated in 105 unison.

8. In a machine for laying out cards, papers, envelopes, &c., for bordering, the combination of a frame 15 consisting of the arms 10 and 12 mounted on the rods 9 and 13, and 110 the post 11, joining said arms, spring-pressed gage-pins carried by said frame, an arm 7 depending from said rod 9, a weighted cord attached to an end of said arm pulling it in one direction, means for actuating the latter in 115 120 an opposite direction, a lever 28 adapted to be actuated by said arm, a spring for holding said lever in position, a frame, a movable platform thereon, a rod attached to the under side thereof, clamps mounted on said rod, 125 springs for holding said clamps in position, a connection from said lever 28 to one of said clamps, and means for actuating said clamps in unison, whereby said platform can be reversed in direction. 130

9. In a machine for laying out cards, papers, envelopes, &c., for bordering, the combination of a frame, a platform thereon, a rod attached to the under side thereof, spring-

actuated clamps mounted upon said rod, means for intermittently actuating one of said clamps, the other of said clamps adapted to prevent the backward movement of said platform, spring-pressed gage-pins supported above said platform, and means for raising and lowering said gage-pins.

10. In a machine for laying out cards, papers, envelops, &c., for bordering, the combination of a frame, a platform thereon, a rod attached to the under side thereof, spring-actuated clamps mounted on said rod, means

for intermittently actuating one of said clamps, spring-pressed gage-pins supported above said platform, means for raising and lowering said gage-pins, and a stop for checking the forward movement of said intermittently-actuated clamp, and preventing the platform from being jerked too far.

HARRY G. TURNER.
